VASE

Albert R. Thomas, Phoenix, Ariz.

Application July 23, 1936, Serial No. 92,239

11 Claims. (Cl. 47—41)

This invention relates to new and useful improvements in vases.

This application is filed as an improvement on my co-pending application filed March 6, 1936, Serial No. 67,519 which has matured into Patent No. 2,062,684.

One object of the invention is to provide an improved vase which is particularly adapted for use in cemetery grounds for holding or supporting floral decorations.

Another object of the invention is to provide an improved vase in which an inner receptacle for holding floral decorations is provided, the construction of the vase being such that this inner receptacle may be supported at various elevations.

An important object of the invention is to provide an improved vase of the character described, including an outer shell or casing and an inner receptacle for holding floral decorations telescoping said shell, the construction of the inner receptacle being such that it may be supported in an upright position so that the flowers may project from its upper end, or said receptacle may be reversed or inverted, whereby when so inverted it will serve to close the upper end of the outer shell or casing.

A further object of the invention is to provide an improved vase including a slideable inner receptacle or container for supporting floral decorations, the vase being mounted so that its upper end is substantially flush with the ground or other support, whereby a lawn mower, or other device, may be readily passed over the vase, and also whereby the vase does not form an obstruction over which persons might trip.

Still another object of the invention is to provide a vase which is so constructed that various types of inner receptacles or containers may be used therein without necessitating any change or modification of the outer shell or casing of said vase; the inner receptacles of both this invention as disclosed herein, and those of my co-pending application above referred to, may be readily interchanged and used with the outer shell or casing.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a vertical, sectional view of a de-

vice constructed in accordance with the invention, showing the receptacle in its lowermost position,

Figure 2 is a similar view showing the receptacle in its raised position,

Figure 3 is a vertical detail showing the receptacle tilted so as to be disengaged from and to pass the stop,

Figure 4 is a similar view showing the receptacle engaging the stop,

Figure 5 is a horizontal, cross-sectional view taken on the line 5—5 of Figure 1,

Figure 6 is a plan view of the receptacle,

Figure 7 is a view similar to Figure 1, showing the receptacle in an inverted position,

Figure 8 is a plan view of the receptacle in an inverted position,

Figure 9 is a vertical sectional view of a modified form of the invention,

Figure 10 is a view similar to Figure 1, showing a modified form of the invention attached to a marker,

Figure 11 is a plan view of this form of the invention, showing a ring attached to the casing, and

Figure 12 is a plan view of the vase mounted in a marker.

In the drawings, the numeral 10 designates an upright, metal casing or shell which is adapted to be embedded in the ground, or in concrete, or other suitable support. The upper edge of the casing is provided with an annular flange 11, which flange is formed so as to extend outwardly, as well as inwardly from the casing wall. When the casing is placed in an opening, or hole A in the ground, or other base, the outwardly extending portion of the flange engages the ground surface to limit the downward movement of the casing and cause the upper end of the casing to be flush with the ground. The bottom of the casing or shell is provided with an axial opening 12 through which water, dirt or other matter may drain.

An elongate, cylindrical receptacle or container 13 is slidably mounted within the shell or casing. The outer diameter of the receptacle is less than the inner diameter of the shell, while said receptacle has a sliding fit within the inwardly extending portion of the annular flange 11. With such arrangement, the inwardly directed portion of the flange overhangs the annular space formed between the receptacle and shell, whereby water, dirt and other extraneous matter will not readily enter this space. The upper end of the cup is closed by a circular head 55

or cap 14 which head is preferably fastened to the upper end of the receptacle. This head may be made of bronze or any other suitable material and could, if desired, be made removable 5 from the receptacle. The cap is provided with a plurality of openings or perforations 14' which extend entirely therethrough, so as to form a frog or holder for the stems of flowers, fern, and the like. The head has a horizontally extending 10 boss or projection 15 at one side thereof, and when the receptacle is placed within the shell and lowered thereto, said boss engages the flange 11 to limit downward movement of the receptacle within the shell.

15 As clearly shown in Figure 1, the head 14 is curved in a long arc and its highest point does not project a great distance above the flange 11, whereby the wheels of a lawn mower, or other device, may readily pass thereover. The curvature 20 of the head does not offer any obstruction and causes the receptacle to be substantially flush with the ground level, and therefore, the vase may be walked over without danger of tripping. This is an important feature of the invention because heretofore, devices of this nature have projected above the ground level and not 25 only caused persons to trip thereover but prevented the passage of a lawn mower, or other similar device thereover.

30 The bottom 13' of the receptacle 13 is provided with a downwardly extending marginal lip or rim 16. An axial sump or recess 17 is formed in the bottom 13' and receives a ring 18, or other similar means which may be used for 35 lifting purposes, as will be explained. A portion of the marginal lip or rim 16 is extended to form a projection 19 and it is preferable that this projection be in vertical alignment with the boss or projection 15 formed on the head or 40 cap 14.

Within the shell or casing 10 and substantially at the midportion thereof, an arcuate lug or rest 21 is located. The lug is substantially triangular in shape in cross-section and, as clearly shown in 45 Figures 1 and 2, the upper surface or face of the lug is inclined upwardly from the wall of the shell. With such arrangement, as the inner receptacle or container 13 is lowered within the shell or casing, it will be obvious that since the 50 projection 19 formed on the lower end of the receptacle is inclined downwardly, this projection will readily engage the upper inclined face of arcuate lug 21. Since the receptacle has a diameter which is substantially equal to the diameter 55 of the annular flange 11, said flange will serve to guide the receptacle into the shell or casing. Therefore, as the receptacle is lowered vertically within the casing the projection 19 will engage the arcuate lug 21, as shown in Figure 2, and 60 further downward movement of said receptacle is prevented, whereby said receptacle is supported in this position.

In the event that the projection 19 should be misaligned vertically with the lug 21 so as not 65 to strike the same as the receptacle is lowered within the shell, it is noted that the projecting rim or lip 16 formed on the lower edge of the receptacle will, when the receptacle is lowered axially within the casing engage the arcuate lug 70 21 to support the receptacle in this intermediate position. However, since the projection 19 is comparatively narrow, while the lug 21 is arcuate, it will be obvious that it is not likely that the projection will miss said lug.

75 With the receptacle in the position shown in

Figure 2, the lug 21 is engaged by the projection 19 and the receptacle 13 is supported within the upper end of the casing 10. The upper portion of the receptacle is projecting upwardly from the ground level at this time. It may remain in this 5 position for any length of time and suitable flowers may be inserted through the opening 14' of the head 14 so as to be supported therein.

When it is desired to move the receptacle 13 to its lowermost position within the casing or 10 shell 10 so that the head 14 is substantially flush with the ground level, it is only necessary to tilt the inner receptacle to the position as shown in Figure 3. Such tilting movement is possible because although the inner receptacle has substantially a sliding fit through the flange 11, yet 15 there is sufficient clearance to permit this tilting movement. As the lower end of the receptacle 13 is moved to one side to engage the wall of the casing or shell, the projection 19 is moved 20 clear or out of alignment with the lug 21. When this occurs further downward movement of the receptacle is possible.

Continued downward movement of the receptacle axially within the shell or casing after it 25 has cleared the lug 21, will cause the rim or lip 16 at the bottom of the receptacle to engage a tapered stop lug or boss 22 which projects inwardly from the wall of the shell or casing 10. The lug 22 is located at the lower end of the 30 casing and projects inwardly therefrom. Located diametrically opposite the tapered lug 22 and disposed in a horizontal plane slightly thereabove, is an arcuate lug 23 which is similar to the lug 21, except that it is inverted. As clearly 35 shown in Figures 1 and 2, the lug 23 is triangular in cross-section and has its under surface undercut as shown at 23'. The lug 23 is in vertical alignment with the lug 21 and is formed preferably integral with the wall of the shell or casing 40 10.

After the inner receptacle 13 has been disengaged from the upper lug 21 and moved downwardly within the shell or casing 10, it is obvious that the projection 19 at the lower end of the receptacle will first strike the inclined surface of 45 the inverted lug 23. This will cause the lower end of the receptacle to be moved toward the opposite wall of the shell or casing and into engagement with the tapered upper surface of the lug 22. By the time the lip or rim 16 at the lower 50 end of the receptacle strikes the lug 22, the projection 19 which is an extension of the rim or lip 16 has cleared the lower end of the lug 23. Continued downward movement of the receptacle causes the tapered surface of lug 22 to move the 55 receptacle back toward the lug 23 and since the projection 19 has cleared the lower edge of the lug 23, it will be obvious that said projection will be moved beneath the lug 23. When this occurs 60 it will be obvious that upward displacement of the receptacle within the casing or shell 10 is prevented by the engagement of said projection beneath the lug 23, as shown in Figure 1.

When it is desired to disengage the receptacle 65 so as to remove the same from the shell, it is only necessary to grasp the inner receptacle by inserting the fingers within the opening 14' in the head. When this is done the lower end of the receptacle 13 may be swung toward the wall of the casing 10 adjacent the lug 22. This swinging 70 of the lower end of the receptacle will disengage the projection 19 from beneath the lug 23 and will permit the receptacle to be moved upwardly and thereby removed from the casing. It is noted that 75

during the upward movement the projection 19 will readily pass the lug 21 because of the particular inclination of said lug which permits the projection to easily pass thereby.

5 It is noted that the casing or shell is inserted in the ground or other base, and when so inserted the flange 11 at the upper edge of said shell is substantially flush therewith. If desired, this flange may be readily used as a name plate for the deceased. The opening 12 in the bottom of the casing 10 provides a suitable drain for water, dirt or other extraneous matter which may find its way into the casing. The receptacle may readily be lowered into the casing and may be supported either by the upper lug 21, whereby the upper portion of said receptacle is above ground, or said receptacle may be moved to its lowermost position as shown in Figure 1, at which time the head of said receptacle is substantially flush with the ground level. It is noted that when the receptacle is in its lowermost position accidental disengagement of the receptacle from within the casing is prevented because the projection 19 is engaged beneath the lowermost lug 23.

25 When the receptacle is within the casing in an upright position, as shown in Figure 1, the projection 19 at the lower end thereof is engaging beneath the lug 23 as has been described, while the projection 15 on the head is overlying the flange 11. When it is desired to reverse or invert the receptacle 13 it is only necessary to remove the same from the casing as above set forth. The receptacle is then turned over with the head 14 lowermost and is inserted into the shell or casing 30 in this manner. The projection 15 on the head 14 is passed by the upper lug 21 in the same manner as the projection 19 clears the same, that is, by tilting the receptacle. When the receptacle reaches its lowermost position the projection 15 35 on the head 14 engages beneath the lowermost lug 23 (Figure 7) while the projection 19 overlies the flange 11 at the upper edge of the casing. It will be obvious that the bottom of the receptacle in this case becomes the top and serves to close off the casing 10 whereby extraneous matter is prevented from falling thereto. The receptacle may be removed from this position by merely grasping the ring 18 which is provided at the center of the bottom of the receptacle 13. It is noted 40 that this is a feature of the invention because when there are no floral decorations, it is desirable to close the casing so as to prevent dirt, or other matter from falling therein.

50 In Figure 9, a modified form of the invention is shown. In this form the lug 23 and tapered lug 22 are eliminated from the inner wall of the casing. The receptacle 13 is exactly the same as in the first form except that the head 14 thereof is provided with an annular flange 14a which 55 flange overlies the flange 11 at the upper end of the casing. For holding the receptacle 13 in this form in its lowermost position so as to prevent water from floating the receptacle upwardly within the casing a suitable chain 24 may be secured to the bottom of the receptacle and fastened to the bottom of the casing as clearly shown in Figure 9. The upper lug 21 is provided in this form and the supporting of the receptacle in an intermediate position by the lug is accomplished in the same 60 manner, since the receptacle is provided with the projection 19 for engaging said lug. Thus, it will be seen that the only difference between this form and that described and shown in Figures 1 to 8 is that the lug 22 and lug 23 are omitted and a 65 chain 24 substituted therefor for holding the re-

ceptacle in its lowermost position. Also the head 14 is provided with the overlying annular flange 14a, and this flange may be used as a name plate, if desired. It is obvious, of course, that if the flange 14a is provided the receptacle cannot be 5 inverted as in the first form.

70 In Figures 10 to 12, inclusive, I have shown still another form of the invention, wherein the vase is mounted within a suitable tablet or marker plate 25. In this form, the receptacle is exactly 10 the same as that shown in the form shown in Figures 1 to 8, there being no change in said receptacle. In place of the outer shell or casing 10 a slightly modified form of casing 10' is provided. The interior of this shell or casing is 15 made exactly as the casing 10 in Figure 1, being provided with an upper lug 21' and a lower lug 23a, as well as a tapered lug 22'. The bottom of the casing 10' instead of being closed and provided with the opening 12 is entirely open, as 20 clearly shown in Figure 10. The insertion or removal of the receptacle 13 within the casing 10' is accomplished exactly as in the form shown in Figures 1 to 8 and a description of the operation or use of the receptacle 13 within the casing 10' 25 is deemed unnecessary.

For supporting the casing 10' within the tablet or plate 25 the upper end of said casing is provided with a flange 11' similar to the flange 11 in the first form. A boss 27 is located at one side 30 of the casing 10', being disposed just below the flange 11' and being preferably made integral with the casing 10'. A similar boss 28 is located diametrically opposite the boss 27, as is clearly shown in Figures 11 and 12. The plate or marker 35 25 is provided with a circular opening 25' which is arranged to receive the casing 10'. The boss 27 is provided with a shoulder 27' upon which the marginal edge portion adjacent the opening 25' of the plate 25 rests, whereby after the casing is 40 inserted in the ground and the marker placed thereover, the marker is supported on the shoulder 27'. The boss 28 is provided with a groove 28' which is arranged to be engaged by a lip or projection 29 which is formed on the plate 25 by 45 cutting a recess 30 therein, as is clearly shown in Figures 10 and 11.

In securing the marker or plate 25 to the casing 10', it will be seen that the lip 29 formed at one side of the marker adjacent the circular opening 50 25' therein is engaged in the groove 28' formed between the boss 28 and the overhanging portion of the flange 11'. The outer edge of the flange 11' is formed with an extension 11a which is located adjacent the recess 30 in the plate 25, 55 whereby when the projection 29 engages in the groove 28', the extension 11a lies within the recess 30. At the same time the side diametrically opposite the boss 28 of the marker, is supported on the shoulder 27' formed at the upper 60 end of the boss 27, and from the above, it will be seen that with this arrangement the casing 10' is securely mounted within the plate 25. It is noted that the provision of the plate or marker does not in any way interfere with the operation or use 65 of the receptacle 13 which may be removed from or inserted within the casing 10' at any desired time. It is further pointed out that the receptacle 13 may be, if desired, inverted within the casing 10' in the same manner as the receptacle 70 13 may be inverted within the casing 10.

The marker in which the casing 10' is mounted may be of any desired shape or form. The casing 10' has been shown as removably mounted or secured within this marker, but it is obvious that, 75

- if desired, the casing could readily be made integral with said marker. Attention is called to the fact that all of the inner receptacles shown in the various forms herein described are interchangeable with any of the casings or shells which have been shown. This is an important feature of the invention as it permits the interchangeability of the various type receptacles with the various casings or shells.
- 5 10 What I claim and desire to secure by Letters Patent is:
1. A vase including, a casing having an open upper end, a receptacle slidably mounted within said casing, a lug located at substantially the mid-portion of the casing within the same, means on the lower end of the receptacle for engaging said lug, whereby the receptacle is supported within the casing so that a portion of the receptacle extends from the upper end of said casing,
  - 15 20 the receptacle having an outer diameter less than the inner diameter of the casing whereby said receptacle may undergo a tilting movement so as to disengage the means from said lug to permit the receptacle to be lowered to its lowermost position, and means at the lower end of the casing for engaging the first named means on the lower end of the receptacle to hold the receptacle in its lowermost position in the casing.
  - 25 30 35 40 45 50 55 60 65 70 75 2. A vase including, a casing having an open upper end substantially flush with the ground level, a receptacle having a closed top with a plurality of openings therein for receiving and holding floral decorations, said closed top lying substantially flush with the ground, whereby the receptacle forms substantially no obstruction when in place within the casing, means for supporting the receptacle at various elevations in the casing, and means for locking the receptacle in its lowermost position in said casing.
  3. A vase including, a casing having an open upper end and adapted to be embedded in the ground, an inner receptacle slidable vertically within the casing and capable of undergoing a tilting movement therein, a projection on the inner wall of the casing arranged to be engaged by the lower end of the receptacle to support said receptacle in an intermediate position, said receptacle being disengaged from the projection when tilted, a second projection at the bottom of the casing within the same, and a complementary projection on the lower end of the receptacle cooperating with said second projection for maintaining the receptacle within the bottom of the casing, the tilting of the receptacle disengaging the cooperating projections to permit removal of the receptacle.
  4. A vase including, a casing having an open upper end and adapted to be embedded in the ground, an inner receptacle slidable vertically within the casing and capable of undergoing a tilting movement therein, a projection on the inner wall of the casing arranged to be engaged by the lower end of the receptacle to support said receptacle in an intermediate position, said receptacle being disengaged from the projection when tilted, and means at the lower end of the casing for locking the receptacle in its lowermost position in the casing.
  5. A vase including, a casing having an open upper end substantially flush with the ground level, a reversible receptacle having a closed top with a plurality of openings therein for receiving and holding floral decorations, said closed top lying substantially flush with the ground, whereby the receptacle forms substantially no

obstruction when in place within the casing, the bottom of the receptacle being flat so as to lie substantially flush with the ground when the receptacle is reversed within the casing, and means for supporting the receptacle at various elevations in the casing.

6. A vase including, a casing having an open upper end and adapted to be embedded in the ground, an inner receptacle slidable vertically in said casing, an arcuate projection of substantial length on the inner wall of the casing arranged

10 to be engaged by the lower end of the receptacle to support said receptacle in an intermediate position within the casing, there being a clearance between the casing and receptacle to permit the receptacle to undergo a tilting movement, whereby said receptacle is disengaged from said projection to permit its lowering to the bottom of the casing.

7. A vase including, a casing having an open upper end and adapted to be embedded in the ground, an inner receptacle slidable vertically in said casing, an arcuate projection of substantial length on the inner wall of the casing, and a lug on the lower end of the receptacle adapted to engage the arcuate projection to support the receptacle in an intermediate position in the casing, said lug being relatively narrow in width

15 so as to facilitate its engagement with the projection, there being a clearance between the casing and receptacle to permit the latter to undergo a tilting movement, whereby the lug may be disengaged from said projection and moved to its lowermost position.

8. A vase including, a casing having an open upper end and adapted to be embedded in the ground, an inner receptacle slidable vertically in said casing, an arcuate projection of substantial length on the inner wall of the casing, a lug on the lower end of the receptacle adapted to engage the arcuate projection to support the receptacle in an intermediate position in the casing, said lug being relatively narrow in width

20 25 30 35 40 45 50 55 60 65 70 75 80 85 90 so as to facilitate its engagement with the projection, there being a clearance between the casing and receptacle to permit the latter to undergo a tilting movement, whereby the lug may be disengaged from said projection and moved to its lowermost position, and means for locking the receptacle in its lowermost position within the casing.

9. The combination with a marker plate having an opening therein, of a vase having means for securing said plate thereto after the vase is embedded in the ground.

10. The combination with a marker plate having an opening therein of a vase including, a casing having projections at its upper end, and a receptacle for floral decorations slidable vertically in the casing, the projections on the casing being located diametrically opposite each other, whereby the marker plate may be engaged therebeneath after the casing has been embedded in the ground.

11. The combination with a marker plate having an opening therein of a vase including, a casing having projections at its upper end, and a receptacle for floral decorations slidable vertically in the casing, means for supporting the receptacle at various elevations within the casing, the projections on the casing being located diametrically opposite each other, whereby the marker plate may be engaged therebeneath after the casing has been embedded in the ground.
